UNITED STATES PATENT OFFICE.

WILLIAM J. KERR, OF SMETHPORT, PENNSYLVANIA, ASSIGNOR OF ONE-FOURTH TO
THOMAS E. HUNGIVILLE, OF SMETHPORT, PENNSYLVANIA.

PROTECTIVE APPARATUS FOR MOVING-PICTURE BOOTHS.

1,091,662.

Specification of Letters Patent. Patented Mar. 31, 1914.

Application filed April 12, 1913. Serial No. 760,811.

To all whom it may concern:

Be it known that I, WILLIAM J. KERR, a citizen of the United States, residing at Smethport, in the county of McKean and State of Pennsylvania, have invented certain new and useful Improvements in Protective Apparatus for Moving-Picture Booths, of which the following is a specification, reference being had therein to the accompanying drawing.

This invention relates to improvements in fire prevention and protective apparatus.

It is particularly adapted for use in connection with kinetoscopes wherein a highly inflammable film is operated in close proximity to an electric arc.

In moving picture theaters the projecting apparatus is, as a rule, positioned in a small inclosure or booth, this booth being in the better forms of construction made of sheet metal. It is well known that the inflammable film very often becomes ignited in some manner resulting in destructive fires. Even in cases where the flames are confined to the booth and prevented from igniting the structure of the theatre, the sight of flames spouting from the opening in the front of the booth through which the rays of light pass is very apt to excite an audience to a high pitch and cause a panic.

An object of my invention is to provide an apparatus which greatly reduces the liability of the film becoming ignited and, in case a fire does occur in a booth, to prevent the flames from extending without its confining walls.

Another object is to provide a communication between the reel holding cases and a suitable exhaust duct leading without the building thereby preventing accumulation of gases within the reel cases and providing a relief duct in case the reel becomes ignited thereby preventing explosions.

Other objects will appear in the specification and claims.

In the drawings, Figure 1 is a partial vertical sectional view through a moving picture booth showing the kinetoscope and my improved apparatus. Fig. 2 is a front view showing a portion of my improved apparatus detached from the walls of the booth.

In the drawings, the numeral 1 indicates the floor of a moving picture machine booth.

2 is the front wall and 3 the roof of the booth.

A kinetoscope supporting table 4 is shown mounted upon legs 5, the numeral 6 indicating the lantern which may be of any type, the details of the kinetoscope or projecting apparatus being unimportant as concerns my invention. On the front portion of the table 4 is mounted the casing 7 which contains the film feeding apparatus. A tube 8 extends a short distance and carries the projecting lens. A film or reel box 9 is mounted above the frame 7 and a second box 10, similar to the box 9, is mounted beneath the table 4. A reel containing the film is placed in one of the boxes and is fed through the casing 7 to the other box, these boxes being usually of sheet steel having tightly closed lids. Even though the greatest of precaution is taken to protect the film, which is necessarily manufactured of highly inflammable material, the frequency of fire and explosions with such apparatus is well known.

In order to eliminate the danger of panics resulting from the sight of flames seen to issue from the picture booths, I have provided in the front wall of my booth a metallic cone 11 making a tight joint with the tube 8 and extend it forward to the front wall of the booth. The angle of slope to the walls of the cone is sufficiently large to prevent any interference to the light rays. When, as in the instance illustrated in the drawings, double projection apparatus is used, I insert in the outer wall of the booth a large pan-shaped metallic casing 12 and in the bottom of this casing insert the two cones 11 which lead back to the lenses of the machines. By means of this apparatus I therefore am able to make the front wall of the booth continuous and unbroken. Any fire appearing in the booth is not visible from the front as is usually the case where an aperture is cut through the front walls for the passage of the light rays.

As a further protection from fire and explosions I have formed a rectangular chamber 13 which may be secured by ears 14 in the front wall of a booth connecting the top of the chamber by a large flue 15 either to a chimney or exhaust apparatus. Flues 16 connect each of the reel containing

cases with the interior of the chamber 13 thereby providing a vent through which the gases or smoke can find a ready exit.

What I claim is:

- 5 1. The combination with a projecting apparatus and its lens, of an inclosing booth, and a non-inflammable tube extending from an aperture in the booth to the lens of the apparatus.
- 10 2. The combination with a projecting apparatus and its lens, of an inclosing booth, and an opaque tube connecting an aperture in the booth with the lens of the apparatus.
- 15 3. The combination with a projecting apparatus and its lens, of an inclosing booth, and a non-inflammable opaque tube connect-

ing an aperture in the front of the booth with the said lens.

4. The combination with a moving picture apparatus and its reel inclosing casings, of an apparatus inclosing booth, and flues connected with the said reel casings and extending to points outside of the booth, the said flues adapted to be connected with an exhaust apparatus. 26

In testimony whereof I affix my signature, in presence of two witnesses.

WILLIAM J. KERR.
